UNITED STATES PATENT OFFICE

SAMUEL KLASSTORNER, OF CHICAGO, ILLINOIS, ASSIGNOR TO FAITH MFG. CO., OF CHICAGO, ILLINOIS, A CORPORATION OF ILLINOIS

DESIGN FOR A RADIATOR CAP

Application filed May 27, 1932. Serial No. 43,914. Term of patent 7 years.

To all whom it may concern:

Be it known that I, SAMUEL KLASSTORNER, a citizen of the United States, residing at Chicago, in the county of Cook, and State of Illinois, have invented a new, original, and ornamental Design for a Radiator Cap, of which the following is a specification, reference being had to the accompanying drawing forming part thereof.

Fig. 1 is a top plan view of a radiator cap showing my new design; and
Fig. 2 is a side elevational view of the same.
I claim:

The ornamental design for a radiator cap, as shown.

In witness whereof, I hereunto subscribe my name, this 20th day of May, 1932.

SAMUEL KLASSTORNER
